UNITED STATES PATENT OFFICE.

CHARLES A. DEUSCHER, OF NEW YORK, N. Y., ASSIGNOR TO THE CUTLER-HAMMER MFG. CO., OF MILWAUKEE, WISCONSIN, A CORPORATION OF WISCONSIN.

CONNECTER.

1,403,298.

Specification of Letters Patent. Patented Jan. 10, 1922.

Application filed October 2, 1920. Serial No. 414,280.

To all whom it may concern:

Be it known that I, CHARLES A. DEUSCHER, a citizen of the United States, residing at New York, in the county of Bronx and State 5 of New York, have invented new and useful Improvements in Connecters, of which the following is a specification.

This invention relates to a connecter.

The connecter to which the invention more 10 particularly relates comprises a conductor by which a resistor of an electric heater may be connected to a terminal thereof.

An object of the invention is to provide an improved connecter.

15 Another object is to provide a connecter which may be firmly and rigidly connected with a resistor or other conductor.

Another object is to provide a connecter which when joined to a resistor will not be 20 loosened when heated repeatedly.

Another object is to provide a connecter so connected to a resistor and having such inherent characteristics that the terminal to which the connecter is connected is maintained at a relatively low temperature.

Another object is to provide an improved connection between a resistor and a connecter.

Another object is to provide a strong and 30 durable low resistance connection between a resistor and a connecter.

Another object is to provide a connection between a connecter and a resistor which will not work loose under repeated wide 35 fluctuations in temperature.

Another object is to provide a connection between a resistor and a connecter which will not be affected by high temperatures.

Another object is to provide an improved 40 method of joining a conductor to a connecter.

Other objects and advantages will herein-after appear.

The views of the drawings are:

45 Fig. 1 shows a connecter blank in the form of a rod;

Fig. 2 shows the connecter blank with one end flattened;

Fig. 3 shows the connecter with the flat- 50 tened end twisted to form a groove therein;

Fig. 4 shows the connecter with the end of the resistor arranged in the groove thereof;

Fig. 5 shows the connecter with the

grooved end thereof partly contracted on 55 the entwined resistor; and

Fig. 6 shows the connecter with its grooved end contracted into intimate contact with the entwined resistor.

The connecter may be made of any suit- 60 able metal or alloy and of such cross section that it is rigid and the conductivity thereof is greater than that of the resistor which it is to connect to a terminal. A connecter of nickel-copper has been found to be suitable 65 for this purpose.

The connecters are formed in the following manner:

Blanks 1 of the required length and in the 70 form of rods are provided.

One end of the rod is flattened.

The flattened end 2 is then twisted to form groove 3.

When a helical resistor 4 is to be joined 75 to a connecter, the helices at the end 5 thereof are first stretched out and then arranged in one of the grooves 3 of the connecter. The connecters may, of course, be employed to connect other kinds of conductors to terminals.

The grooved end of the connecter is then hammered, swaged or otherwise contracted crosswise whereby the entwined end of the resistor is firmly gripped by the grooved connecter, and the resistor and connecter are 85 in intimate contact.

During the process of contraction, the 90 grooved end of the connecter is deformed so that it grips the entwined resistor. Thus the resistor and connecter are joined together in intimate contact, so that the connection therebetween is of very low resistance.

The resistor is wrapped around the connecter and is tightly gripped thereby, a 95 great proportion of the peripheral surface of the entwined resistor being in intimate contact with the connecter.

The free end of the connecter may be arranged in a manner suitable for connection 100 to the type of terminal employed, or if desired, both ends may be grooved for connection to conductors or resistors.

The connection is strong and durable and 105 is not affected by heat at the operating temperature of the heater.

The resistor forming the heating element of an electric heater may be subjected to

high temperature for prolonged periods. The variation in temperature when the resistor is working and when not working may be very great.

5. The connection between the connector and the resistor of such heaters should be able to withstand such high temperatures and such great variations in temperature so that the heater may be efficient and of long life.

10. Among the advantages of such a connection between the resistor and the connector are the following:

It is of low resistance.
It is durable.

15. It is highly efficient.

It is not affected by high temperatures and wide variations thereof.

The invention contained herein is of course susceptible of other embodiments and

20. adaptations.

The invention claimed is:

1. A connector for connecting an electric conductor to a terminal comprising a conducting rod having a groove formed in one

25. end for the reception of the conductor and the other end arranged for connection to the terminal.

2. A connector for connecting an electric conductor to a terminal comprising a conductor having a spiral groove formed in one end thereof for the reception of the electric conductor, about which the walls of the groove may be forced into intimate contact.

3. A connector for connecting a conductor 35 to a terminal comprising a rod having a groove formed in the periphery thereof for the reception of the conductor, the connector and entwined conductor being contracted crosswise into intimate contact.

40. 4. The method of joining a conductor and a connector which consists in arranging the ends thereof in complementary conformation and then deforming the engaged ends to bring the same into intimate contact.

45. 5. The method of joining a connector and a conductor, which consists in arranging ends thereof in intertwined relation and then deforming the intertwined ends to bring the connector and conductor into intimate contact.

50. 6. The method of joining a conductor and a connector, which consists in arranging the ends thereof in entwined relation and then

subjecting the entwined ends to pressure to bring the conductor and the connector into intimate contact.

7. The method of joining a conductor and a connector which consists in arranging the ends thereof in entwined relation and then compressing the connector about 60 and into intimate contact with the entwined conductor.

8. The method of joining a conductor to a rod like connector which consists in flattening one end of the connector, twisting the 65 flattened end to form a groove therein, arranging the conductor in the groove, and contracting the connector into intimate contact with the conductor.

9. The method of joining a conductor to 70 a rod like connector which consists in flattening one end of the connector, forming the flattened end to provide a groove therein, arranging the conductor in the groove, and subjecting the overlapping connector and 75 conductor to pressure to bring the same into intimate contact.

10. Means for connecting a conductor to a terminal, comprising a connector having in one end thereof a groove in which the conductor is arranged with the grooved connector contracted into intimate contact therewith, the other end of the connector being arranged for connection to the terminal.

85. 11. Means for connecting a conductor to a terminal, comprising a connector having the conductor overlapping one end thereof, the connector being contracted into intimate contact with the conductor, the other end of 90 the connector being arranged for connection to the terminal.

12. A connector for connection to an electric conductor comprising a conducting rod having a groove formed in one end for the 95 reception of the conductor.

13. A connector for connection to an electric conductor having a spiral groove formed in one end thereof for the reception of the electric conductor, about which the walls of 100 the groove may be forced into intimate contact.

In witness whereof, I have hereunto subscribed my name.

CHARLES A. DEUSCHER.
